UNITED STATES PATENT OFFICE.

SARAH RISER, OF PHILADELPHIA, PENNSYLVANIA.

DESIGN FOR A NECKTIE.

Application filed February 4, 1928. Serial No. 25,203. Term of patent 7 years.

To all whom it may concern:

Be it known that I, SARAH RISER, a citizen of the United States, residing in Philadelphia, county of Philadelphia, State of Pennsylvania, have invented a new, original and ornamental design for a Necktie, of which the following is a specification, reference being had to the accompanying drawing, which forms a part thereof,

The figure is a front view of a necktie embodying my design.

I claim:

The ornamental design for a necktie, as shown.

In testimony of which invention, I have hereunto set my hand, at Philadelphia, on this 28th day of January, A. D. 1928.

SARAH RISER.
